EVAPORATION COOLING FOR HORIZONTAL
PISTON MOTORHans List and Egon Niedermayer, Graz, Austria;
said Niedermayer assignor to said ListApplication March 26, 1949, Serial No. 83,693
In Austria April 7, 1948

3 Claims. (Cl. 123—41.31)

1

The invention relates to an evaporation cooling for horizontal piston motors (reciprocating engines), and substantially consists in that the cooling water space and the evaporation surface of the cooling water in the cooling water space extend over the entire length of the cylinder and of the crank case and over the entire width of the crank case, yet do not exceed the width of the crank case at any point. With the known evaporation cooling systems of horizontal piston motors the cooling water space extends only over the cylinder and over a portion of the crank case, whereby said space has frequently to be enlarged laterally beyond the crank case in order to provide sufficient accommodation for the quantity of water required. Besides, with these known arrangements the upper wall, i. e., the ceiling of the water space is, as a rule, located in part at a lower level so that the evaporation surface of the cooling water is confined to a portion of the cooling water space.

The measure taken according to the invention of utilizing the entire length of the cylinder and of the crank case as well as the entire width of the crank case for the cooling water space and the evaporation surface now enables lodging the greatest possible quantity of cooling water without having to let the cooling water space project over the width of the crank case. Owing to the fact that the evaporation surface of the cooling water extends the full length and width of the machine, the direct heat transfer from the water to the air is improved, and with improved cooling the water consumption is decreased, since in the evaporation on a large surface less water is entrained, while also at high output and overload sufficient cooling is insured due to the large evaporation surface.

The portion of the cooling water space present above the crank case is of special importance for the cooling effect. If the flywheel is arranged adjacent to the cooling water space, this portion of the cooling water space, which may be provided with cooling ribs, is intensively cooled by the air entrained by the flywheel. This further decreases evaporation, diminishes the water loss, and improves the cooling of the cylinder.

Apart from the advantages relating to the cooling effect, there is obtained through the invention an esthetic, smooth, and compact design of the machine, in which the cooling water space ends flush with the crank case and recessed angles and edges are largely avoided, so that the machine can always be kept clean with little effort.

2

The drawing illustrates an embodiment of the invention by way of a diagram.

Fig. 1 is a longitudinal section through the cylinder axis of a horizontal one-cylinder motor, whereas Fig. 2 is a section taken on the line II—II of Fig. 1.

The cooling water space 1 extends over the entire length of the crank case 2, so that not only the cylinder liner 3 of the motor and the parts 4 of the crank case, adjoining the cylinder liner, are washed and cooled by the water, but also the upper wall (ceiling) 5 of the crank case. By this design a great increase of the water surface has been obtained, additionally the crank case, on the cooled wall 5 of which the lubricating oil is splashed from the moving organs of the motor, is also cooled. These results are attained without the water space having to be advanced laterally beyond the casing. As shown in Fig. 2 the cooling water space 1 is laterally limited according to the contour of the crank case so as to give the motor a compact shape, and a smooth exterior. In the embodiment according to the drawing the space 6, of the crank case 2, is intended for lodging the valve gear and the auxiliary devices of the motor. The fact that this space too is cooled is of lesser importance, but an increase of the cooling water surface is obtained by having the cooling water space extend also above the space 6. The upper wall, i. e., the ceiling of the cooling water space is even, so that the efficient evaporation surface extends over the entire cooling water space, i. e., over the whole length of both the cylinder and the crank case, whereby a most excellent cooling effect is warranted compatible with a minimum consumption of cooling water.

The flywheel 7 is arranged adjacent to the motor casing delimiting the cooling water space. Within the scope of the air current, produced by the rotation of the flywheel, the motor casing and/or the walls of the cooling water space 1 are provided with cooling ribs 8. Hence, the evaporation cooling is intensified by the surface cooling of the cooling water tank so that the cooling water consumption is further reduced.

What we claim is:

1. In an evaporation cooled horizontal piston engine having a horizontal cylinder and crank case, a cooling-water space surrounding the cylinder and extending above the crank case for the entire length and width of the crank case, said cooling-water space having walls which extend approximately vertically to the height of the cooling water level.

2. In an evaporation cooled horizontal piston engine according to claim 1, a flywheel arranged immediately adjacent to one of the vertical walls of the cooling-water space.

3. In an evaporation cooled horizontal piston engine according to claim 2, external cooling ribs on one of the vertical walls of the cooling-water space in an area adjacent to the flywheel.

HANS LIST.
EGON NIEDERMAYER. 10
